SPECTACLE HOLDER

Richard J. McFadyen, Upper Montclair, N.J., assignor to Ketcham and McDougall, Inc., Roseland, N.J., a corporation of New Jersey

Application March 28, 1958, Serial No. 50,215

Term of patent 14 years

(Cl. D17—15)

Fig. 2.

Fig. 1 is a top plan view of a spectacle holder, showing my new design; and Fig. 2 is a fragmentary side elevational view thereof.

Parts are shown broken away in Fig. 1 to indicate indeterminate length. The dominant features of my design reside in the portions shown in full lines.

I claim:

The ornamental design for a spectacle holder, as shown and described.
